(57) **CLAIM**

The ornamental design for a pocket insert device, as shown and described.

DESCRIPTION

FIG. 1 is a top auxiliary view of an embodiment of the pocket protector showing my new design;

FIG. 2 is a front side plan view thereof;

FIG. 3 is a rear side plan view thereof;

FIG. 4 is a first side plan view thereof;

FIG. 5 is a second side plan view thereof;

FIG. 6 is a top plan view thereof; and,

FIG. 7 is a bottom plan view thereof.

The broken lines showing of portions of the pocket insert are for the purpose of illustrating environmental structure and form no part of the claimed design.
